US00D902928S

(12) **United States Design Patent** (10) **Patent No.:** **US D902,928 S**
(45) **Date of Patent:** **** Nov. 24, 2020**

(54) **BLUETOOTH KEYBOARD**

(71) Applicant: **SHENZHEN HASTECH INDUSTRIES CO., LTD.**, Shenzhen (CN)

(72) Inventor: **Shu-Meng Cai**, Shenzhen (CN)

(73) Assignee: **SHENZHEN HASTECH INDUSTRIES CO., LTD.**, Shenzhen (CN)

(**) Term: **15 Years**

(21) Appl. No.: **29/663,121**

(22) Filed: **Sep. 12, 2018**

(30) **Foreign Application Priority Data**

Jul. 12, 2018 (CN) 2018 3 0376486

(57) **CLAIM**

The ornamental design for a Bluetooth keyboard, as shown and described.

DESCRIPTION

FIG. 1 is a perspective view of a Bluetooth keyboard, showing our new design;

FIG. 2 is front elevational view thereof;

FIG. 3 is rear elevational view thereof;

FIG. 4 is left side elevational view thereof;

FIG. 5 is a right elevational view thereof;

FIG. 6 is a top plan view thereof; and,

FIG. 7 is a bottom plan view thereof.

The broken lines shown in drawings represent portions of the Bluetooth keyboard and form no part of the claimed design.

1 Claim, 7 Drawing Sheets
